UNITED STATES PATENT OFFICE.

ORRIN M. SALA, OF CANTON, OHIO, ASSIGNOR TO THE GILLIAM MANUFACTURING COMPANY, OF CANTON, OHIO, A CORPORATION OF OHIO.

TIRE COVER.

Application filed October 20, 1922. Serial No. 595,807.

To all whom it may concern:

Be it known that I, ORRIN M. SALA, a citizen of the United States, residing at Canton, in the county of Stark and State 5 of Ohio, have invented a new and useful Tire Cover, of which the following is a specification.

The invention relates to covers or shields made of sheet fabric or other flexible material, for enclosing or encasing automobile tires and the like; and the object of the improvement is to provide adjustable fastening means for the overlapping ends of the cover, so that the same may be held taut 15 upon and around the tire.

A special object of the improvement is to avoid the use of buttons or like fastening means, which can only be secured at fixed intervals, by the use of a cam clamping fastener secured to the edge of one overlapping end of the cover, and adapted to engage and clamp at any place upon the corresponding edge portion of the other overlapping end of the cover.

Such edge engaging and clamping means may be in the form of a metal base plate having an L-flange along one side forming an abutment jaw spaced from the base plate; and by providing a central opening 30 in the base plate and pivotally mounting a lever upon the other side of the plate, providing a flat cam tongue operable through the opening toward and from the abutment jaw.

The base plate is secured to the edge portion of one overlapping end of the cover, and the corresponding edge portion of the other end of the overlapping cover is entered between the secured edge portion and 40 the abutment jaw, where it may be adjusted endwise and then clamped in place by the cam tongue.

The invention is illustrated in the accompanying drawings, forming part hereof, in 45 which—

Figure 1 is a side elevation of a cover as secured upon a tire;

Fig. 2, a fragmentary enlarged elevation of the overlapping ends of the cover, showing a plan of one edge fastener;

Fig. 3, a longitudinal section of the fastener showing the overlapping edges of a cover secured together by the fasteners, as on line 3—3, Fig. 2;

Fig. 4, a fragmentary cross section of the

same, omitting the overlapping ends of the cover, as on lines 4—4, Figs. 2 and 3;

Fig. 5, a detached perspective view of the fastener body;

Fig. 6, a detached perspective view of the 60 cam lever; and

Fig. 7, a fragmentary perspective view showing the edge portions of the overlapping ends of a cover secured together by the improved fastener. 65

Similar numerals refer to similar parts throughout the several figures of the drawings.

The tire cover 1 may be made of oil cloth or other suitable fabric in the form of 70 an annular sleeve or casing, split around its inner side to form edges 2, to envelop the tire casing proper when it is placed circumferentially thereon, and having a sufficient length to fit tires of a number of sizes by 75 an overlapping of its ends 3 and 3' to a greater or less extent.

The body 4 of the fastener may be an elongated flat plate of metal or the like, having apertures 5 in each end for rivets 6 80 preferably used for securing it to the edge portion of one of the ends of the cover. A flange 7 extends from one edge of the plate inward past the secured edge of the cover, whence an L-tongue or plate 8 extends inward substantially parallel with the body of the fastener and at a spaced interval therefrom. 85

A central opening 9 is provided in the base plate, as by cutting and striking outward 90 ears 10 along each side of the opening, in which ears may be provided bearings 11 for journals or trunnions 12 on the side of a lever 13; which lever may be in the form of a flat strip of metal having one end extending as a straight handle, and the other end bent inward and under to form an L-shaped cam tongue 15, located opposite and spaced from the axis of the trunnions. 95

The parts are so proportioned that when 100 the handle of the lever is swung outward from the base plate, the cam plate will be swung outward through the central opening therein, as shown by broken lines in Fig. 3; and that when the handle is swung 105 inward parallel to the base plate, the cam plate will rotate inward through the opening into a position intermediate the base plate and abutment jaw 8 of the fastener.

For securing overlapping edge portions 110

of a cover together, the lever handle is thrown outward and the free edge is entered laterally under the jaw, after which the handle is swung inward so that the overlapping edges of the cover are clamped between the cam tongue of the lever and the abutment jaw of the body, as shown in Fig. 3.

The abutting face of the jaw may be provided with protrusions or other anti-friction means, to more securely hold the fabric of the cover; and the parts are so arranged that the angle of the L-cam plate must be forced beyond a dead center by a compression of the fabric or a yielding of the abutment jaw, so that the elasticity of these parts serves to hold the cam lever in clamping position by pressing flatwise against the clamping plate, when the handle is swung inward, as shown in Fig. 3.

A fastener is provided on each edge of one overlapping end of the cover, and it is evident that the corresponding free edges of the underlapping end can be engaged in and clamped by the fastener at any place required for an adjustment of the cover to neatly fit a tire; it being understood that after entering the free edge under the abutment jaw, the edges may slide longitudinally upon each other, until a proper adjustment of the cover is attained, whereupon the cam lever is operated to clamp and secure the edges to-

gether in the desired position of adjustment.

I claim:

1. A tire cover having overlapping ends with fasteners on the edges of one end for engaging and clamping the corresponding edges of the other end.

2. A tire cover having overlapping ends with fasteners on the edges of one end having abutment jaws for engaging the edges of the other end, and means for clamping the overlapping edges against the abutment jaw.

3. A tire cover having overlapping ends with fasteners on the edges of one end having abutment jaws for engaging the edges of the other end, and a cam tongue for clamping the overlapping edges against the abutment jaw.

4. A tire cover having overlapping ends with fasteners on the edges of one end, each fastener including a base plate secured to one edge having an abutment jaw spaced from one side thereof, a cam tongue operatively mounted on the other side thereof, for clamping the overlapped edges between the cam tongue and the abutment jaw.

5. A tire cover having overlapping ends with fasteners on the edges of one end for sliding engagement with and clamping upon the corresponding edges of the other end.

O. M. SALA.
